WIRE STRIPPER BLADE

Clyde C. Johnson, Inglewood, Calif.

Application September 27, 1954, Serial No. 32,449

Term of patent 7 years

(Cl. D54—13)

Fig. 1

Fig. 2

Fig. 3

Fig. 4

Figure 1 is a perspective view of a wire stripper blade showing my new design;

Figure 2 is a front elevational view;

Figure 3 is a side elevational view; and

Figure 4 is a bottom plan view.

The dotted lines shown in Figure 1 are for illustrative purposes only.

I claim:

The ornamental design for a wire stripper blade, as shown and described.
